CLAIM

The ornamental design for a trailer mounted mobile laundromat, as shown and described.

DESCRIPTION

FIG. 1 is a top plan view of the trailer mounted mobile laundromat according to the present invention;

FIG. 2 is an elevational view of one end of the trailer mounted mobile laundromat taken along line 2.2 of FIG. 1; FIG. 3 is an elevational view of the opposite end, taken along line 3.3 of FIG. 1;

FIG. 4 is an elevational view of one side of the trailer mounted mobile laundromat according to the present invention; and,

FIG. 5 is an elevational view of the opposite side thereof.
